(57) **CLAIM**

The ornamental design for a camera mountable arm, as shown and described.

DESCRIPTION

This application is related to pending U.S. patent application Ser. No. 14/054,640, filed Oct. 15, 2013, the contents of which are incorporated by reference herein in its entirety. FIG. 1 is a front top right perspective view of a camera mountable arm in an extended configuration;

FIG. 2 is a rear top left perspective view thereof;

FIG. 3 is a rear bottom left perspective view thereof;

FIG. 4 is a left view thereof;

FIG. 5 is a right view thereof;

FIG. 6 is a rear view thereof;

FIG. 7 is a front view thereof;

FIG. 8 is a top view thereof;

FIG. 9 is a bottom view thereof;

FIG. 10 is a rear top left perspective view of the camera mountable arm of FIG. 1 in a folded configuration;

FIG. 11 is a left view thereof;

FIG. 12 is a right view thereof;

FIG. 13 is a rear view thereof;

FIG. 14 is a front view thereof;

FIG. 15 is a top view thereof;

FIG. 16 is a bottom view thereof;

FIG. 17 is a rear top left perspective view of a first component of the camera mountable arm of FIG. 1;

FIG. 18 is a front bottom right perspective view thereof;

FIG. 19 is a left view thereof;

FIG. 20 is a right view thereof;

FIG. 21 is a rear view thereof;

FIG. 22 is a front view thereof;

FIG. 23 is a top view thereof;

FIG. 24 is a bottom view thereof;

FIG. 25 is a rear top left perspective view of a second component of the camera mountable arm of FIG. 1;

FIG. 26 is a front bottom right perspective view thereof;

FIG. 27 is a left view thereof;

(Continued)

FIG. 28 is a right view thereof;
 FIG. 29 is a front view thereof;
 FIG. 30 is a rear view thereof;
 FIG. 31 is a top view thereof;
 FIG. 32 is a bottom view thereof;
 FIG. 33 is a front bottom and left perspective view of a third component of the camera mountable arm of FIG. 1;
 FIG. 34 is a rear top and right perspective view thereof;
 FIG. 35 is a left view thereof;
 FIG. 36 is a right view thereof;
 FIG. 37 is a rear view thereof;
 FIG. 38 is a front view thereof;
 FIG. 39 is a top view thereof; and,
 FIG. 40 is a bottom view thereof.
 The broken lines in the drawing depict portions of the camera mounted arm that form no part of the claimed design.
